Letters Patent No 1261, dated June 19, 1860.

The schedule referred to in these Letters Patent, and making part of the same.

To all whom it may concern:

Be it known that I, Samuel Morgan, of South Norwalk, County of Fairfield and State of Connecticut, have invented or produced a new and original Pattern or Design for Fire Shovel, and I do hereby declare that the following is a full and exact description of the same, referring to the accompanying Photographic Views, in which the same letters indicate like parts in each of the figures:

For the accompanying Photographic Views.

Fig. 1. Shows a front elevation of my new pattern or design for fire shovel, and

Fig. 2. Shows a back side view of the same.

a. is a long narrow flat, curved end bottom. c. is the end and sides, gradually tapering and slightly dishing in its curve, and slanting out from the bottom having a configuration of a concave handle. b. for a new and useful pattern for fire coal or ash Shovel.

I claim a new pattern for a fire coal or ash Shovel, having the shape and configuration illustrated and described.
